E. ANDERSON

GRAIN SEPARATOR

Filed March 16, 1921

UNITED STATES PATENT OFFICE.

EDWARD ANDERSON, OF MINNEAPOLIS, MINNESOTA.

GRAIN SEPARATOR.

Application filed March 16, 1921. Serial No. 452,835.

To all whom it may concern:

Be it known that I, EDWARD ANDERSON, a citizen of the United States, residing at Minneapolis, in the county of Hennepin and State of Minnesota, have invented certain new and useful Improvements in Grain Separators, of which the following is a specification.

This invention relates to grain cleaning devices, and more particularly to rotary means for separating the grain from foreign substances, such as wild oats, weed seeds, or such other matter as will readily pass through an initial screen for initially extracting the chaff from the bulk of the grain.

An object of the invention is to provide improved grain separating means, wherein each kernel is caused first to be rolled around its longitudinal axis and then deposited in a pocket or indent of predetermined size for the purpose of grading, and conducted to a suitable destination.

A further object of the invention is the provision of a device of the class described, wherein the kernels, after passing through the chaff separating screen, fall upon two upwardly diverging surfaces moving constantly in upward direction to cause the kernels to roll down hill as distinguished from some present methods of sliding and grinding back and forth on a wire or perforated metal screen thereby bruising the hulls.

A still further object of the invention is the provision of simple practical, efficient and economic means for grading as to size, and separating as to foreign matter, grains and the like.

The invention consists in the construction, combination and arrangement of parts hereinafter described and claimed.

In the drawings forming part of this specification,

Figure 1 is a side view of my improved device.

Figure 2 is an end view of the same.

Figure 3 is an end view showing the driving gear.

Figures 4 and 5 are perspective views of one end of the separating cylinders.

Figures 6 and 7 are fragmentary perspective views of sections of the peripheral surface of the cylinders showing on an en-

larged scale, the cavities or indents in the surfaces of the cylinders.

Figure 8 is a fragmentary sectional view on line 8—8 of Figure 7.

Figure 9 is a fragmentary sectional view on line 9—9 of Figure 6 showing the adjacent cylinder and the position the kernels assume.

Figure 10 is a similar view, showing two indents in opposite relation.

Figure 11 is a front view, partly in section, of one of the cylinder journals.

Figure 12 is a perspective view, partly in section, of another of the cylinder journals.

A designates the frame, B the chaff separating screen, B' the grain chute, C and C' the wheat and oat separating cylinders, C'' the wheat chute, D and D' the wheat and weed seed separating cylinders and D'' the weed seed chute.

E designates a supply hopper, B'' the chaff slide, C''' the oat slide and D''' the wheat slide, all of said slides serving as means for conducting the material away from the machine.

The screen B is inclined to the left and is suspended on the U hangers 1 and 2 extending laterally across the frame and journaled in the journal boxes 3, so that it may be reciprocated longitudinally of the frame, the screen having the usual perforated floor 4, through which the kernels separated from the chaff, pass. Under the screen is the preferably stationary grain chute B', arranged in parallelism with the screen and having a central contracted spout 5 adjacent one end of the frame. Journaled in the journals B and H respectively, at one end, and in the journals I with their other ends, are the shafts 6, arranged in parallelism, one for each of the cylinders C and C', the journals being positioned so as to bring the two cylinders into peripheral contact and incline the same in opposition to the screen B. Each cylinder is partially surrounded in spaced relation, by a shield 7, the shields extending in opposite directions from a point above and midway between the cylinders to a point below and midway between the cylinders, the lower portion 8, of the shield forming a downwardly and inwardly directed slide, whereby the grain is conducted to the longitudi-

75

105

nal central gap 9 formed between the lower edges of the shields. The upper edges of the shields are also spaced to form the longitudinal central gap 10, to receive the grain from the spout 5.

Mounted directly under the cylinders C and C' are the cylinders D and D', these cylinders being mounted respectively in similar journals and in peripheral contacting relation, but inclined in opposition to the first named cylinders. Further, they are similarly shielded so as to form upper and lower gaps 11 and 12, and slide portions 13.

15 The chute D'' however, is preferably inclined in opposition to the cylinder D and D' to carry the material away from the machine.

The end upon which the supply hopper E is mounted, may be termed, the feed end, of the machine, the latter also constituting the end connected with a source of power. The frame is formed at said feed end with an extension having uprights 14, wherein are journalized the transverse driving shafts 15 and 16, and the crank shaft 17. Rigid on the shaft 15 are the belt pulleys 18 and 19 having belt connection respectively with the pulley 20 on the shaft 17, and the pulley 21 on the shaft 16. A driven pulley 22 has suitable belt connection with a source of power (not shown).

Rigid on each of the shafts 15 and 16, adjacent the uprights 14, and facing one another are the miter gears 23 each meshing with one of the bevel gears 24 of which there is one for each shaft 6. Thus when the shafts are rotated each cylinder of a pair will rotate in opposite direction to its mate as indicated by the arrows in Fig. 3. As shown the cylinders will rotate from below upwards and toward each other, so that kernels of grain falling from above between the cylinders will be agitated by the constant tendency to adhere to the upwardly moving peripheral surfaces of the cylinders (see Figure 9).

For the purpose of maintaining a perfect peripheral contact between the cylinders, and avoiding the necessity of having absolutely true cylinders, I provide both ends of the left hand cylinders C' and D' (Fig. 2) with a spring pressed journal box so that the cylinder will be held under stress of the spring, in contacting relation with the adjacent cylinder. This journal which is designated by the letter G in the foregoing, comprises a vertical plate 25 having a pair of vertically slotted bolt holes 26, said plate formed with a hub having a transverse bore 27, rotatably receiving the shank 28 the latter extending at right angles to the journal box 29 wherein rotates the shaft 6. Oppositely aligned with the bore 27 is the lug 30, said journaled box and lug being adapt-

ed to hold under stress between them the coil spring 31. Obviously, the journal box may thus be slid laterally with respect to the machine frame, while the slotted holes 26 permit the angle of inclination of the cylinders 70

to be changed to meet conditions of the work in hand. The cylinders C and D are provided at the discharge end with the journal H, comprising slotted bolt hole adjustment similar to journal G, but having the journal 75 box 32 formed with transverse trunnions 33. At the feed end of the machine, these cylinders are preferably provided with the journal I shown in Figure 12, wherein the journal box is trunnioned similar to box H, but 80

is formed with a vertical threaded shank 34, having threaded nuts 35 whereby the cross timber 36 may be firmly clamped between them. Thus the cylinders may be adjusted to keep the gears 24 properly aligned 85 with the gears 23. As hereinbefore stated, the cylinders C and D rotate clockwise while C' and D' rotate counterclockwise. Profusely distributed over the entire surface of the cylinders C and C' are the indents in pockets 37, (see Figs. 7 and 8) of a size to loosely receive a kernel of wheat, the side wall 38 and the bottom 39 being so inclined (see Fig. 10) relative to each other and the cylinder so that the bottom 39 will 90

be inclined upwardly and outwardly, when the indent is positioned in the plane of the shafts 6. Thus the grain in the crotch formed by the rolls is caught up in the indents and carried over the top and discharged through the gap 9 on to the chute C''. As indicated in dotted lines in Figure 7, oats cannot lodge in these indents, as the latter are too small. The oats will travel in crotch of the cylinders and be discharged onto the slide C'''.

The cylinders D and D' are pitted or indented in like manner, excepting as to the size of the indent, these latter being of much smaller dimension to catch all small matter such as weed seeds, and the like, which latter are discharged onto the chute D'', while the wheat is discharged from the crotch of the cylinders to the slide D'''.

Figures 6 and 9, serve to illustrate the relative difference in size of the indents, small seeds being shown lodged both in the crotch of the cylinders and in the indents. Figures 4 and 5 serve to illustrate the manner of distributing the indents, which latter may be very closely spaced. The crank 40 of the shaft 17 is connected by means of the connecting rod 41 to the screen B so that the latter will be reciprocated concurrently with the rotation of the cylinders.

I claim:

1. In a machine for separating kernels, a pair of rotatable cylinders in longitudinal peripheral contacting relation and provided with peripheral indents, each indent formed with an undercut kernel-supporting seat, the 130

5 indents of one cylinder opposing and co-operating with those of the companion cylinder to form composite kernel-receiving pockets, the undercut of each indent extending downwardly from the peripheral line of contact between the cylinders.

10 2. A machine for separating kernels of specific size from a mixture of kernels of varying sizes, comprising rotatable cylinders in longitudinal peripheral contacting relation, the axes of rotation thereof lying in an inclined plane, means for rotating said cylinders in a direction away from each other, grain screening devices above said 15 cylinders having a spout for discharging the grain onto and between said cylinders and at a position adjacent the inclined ends thereof, and undercut pockets on the circumferential surface of the cylinders, constructed for a specific size of kernel engaging individual kernels of said specific size to carry them bodily upward, the pockets of one cylinder coacting with those on a companion cylinder and opposing each other 20 along their line of contact.

25 3. A machine for separating grain from foreign substances, consisting of pairs of rotatable cylinders one pair directly above the other, the axes of rotation of the cylinders of each pair lying in an inclined plane, said pairs being inclined in opposite directions, each pair of cylinders being longitudinally in peripheral contact and having 30 cavities of uniform size throughout their circumferential surfaces, the cavities of one pair being larger than those of the other, each cavity being formed with a shoulder capable of holding an individual kernel in a manner to carry the latter from a position 35 midway of and above the cylinders to and over the top thereof, means for discharging grain onto the upper pair of cylinders at a position midway between them and adjacent the elevated end thereof, and means between 40 the pairs of cylinders for conducting the kernels carried over the upper cylinders to

the elevated end of the lower pair of cylinders.

4. In a grain separator, a frame, vertically spaced pairs of cylinders, means adjustably 50 and rotatably supporting the cylinders on the frame, a screening device supported on the frame above the cylinders, and shields enclosing the outer portions of the pairs of cylinders and functioning to guide the 55 screenings from the device to the cylinders and from the latter.

5. In a grain separator, a pair of cooperating cylinders having peripheral grain-separating formation, a shielding device in 60 closing the cylinders at their outer portions and separated above to provide an entrance to the line of contact between said cylinders, said shielding device confining the separated grain in its movement over the cylinders, 65 and means for conveying the separated grain from the shielding device.

6. In a grain separator, superposed pairs of grain separating cylinders, said pairs inclining in opposite directions, a shield for 70 the outer portion of each cylinder separated from the companion shield to provide an entrance space between the cylinders of each pair, said shields of each pair converging on the underside thereof to collect and deliver 75 the separated grain, and a trough receiving the collected grain from the upper pair of shields for delivering the same between the lower pair of shields at the upper end of the lower pair of rolls. 80

7. In a grain separator, superposed pairs of grain separating cylinders, said pairs inclining in opposite directions, a pair of shield sections for each pair of cylinders separated above and below the respective 85 pairs for providing entrance and delivery openings, the shield sections for the upper pair of cylinders delivering into the lower pair of cylinders.

In testimony whereof I affix my signature. 90

EDWARD ANDERSON.
